Primary Examiner — Leanne Was-Englehart*Assistant Examiner* — Alison Davis(74) *Attorney, Agent, or Firm* — WPAT, PC(57) **CLAIM**

The ornamental design for a display, as shown and described.

DESCRIPTION

FIG. 1 is a front perspective view of a display showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The oblique shade line indicates a transparent portion of the claimed design.

1 Claim, 8 Drawing Sheets(56)
